UNITED STATES PATENT OFFICE.

EUGÈNE ODAM, OF PARIS, FRANCE.

PROCESS AND APPARATUS FOR ATOMIZING MATERIALS IN A MELTED STATE.

1,328,446.

Specification of Letters Patent.

Patented Jan. 20, 1920.

Application filed January 2, 1919. Serial No. 269,388.

To all whom it may concern:

Be it known that I, EUGÈNE ODAM, a citizen of the Republic of France, residing at 131 Rue d'Avion, Paris, France, have invented a new and useful Process and Apparatus for Atomizing Materials in a Melted State; and I do hereby declare that the following is a full, clear, and exact description of the invention, which will enable others skilled in the art to which it appertains to make and use the same.

This invention relates to a process for atomizing materials such as metals, chemical products, vitreous materials, etc.; while in a melted condition, according to which the said materials are first heated by the flame and gases produced by the combustion under pressure of a suitable solid, liquid or gaseous fuel and then atomized by the sudden expansion of the said gases in open air.

It further relates to an apparatus for carrying out the said process, consisting, chiefly, of a chamber provided with a furnace suitable for the fuel employed, in which combustion is maintained under pressure, through which passes a pipe for conducting the molten material, the said chamber being furnished with an outlet nozzle into the middle of which extends the end or mouth of the said feed pipe and through which escape the combustion-gases, the sudden expansion of which in the open air causes the atomization of the material.

The following description with reference to the accompanying drawing, given by way of example, will enable the process and the manner of carrying it out to be fully understood.

Figure 1 is a sectional view of one embodiment of the apparatus of the present invention and in which the process may be carried out, and

Figs. 2, 3 and 4 are views of the preferred embodiment, Fig. 2 being a vertical sectional view (with parts in elevation), Fig. 3 a rear elevation of the parts at the upper left-hand side of Fig. 2, and Fig. 4 a cross-sectional view of Fig. 3.

The apparatus consists of a chamber *a* formed by a metal wall *b* covered internally with a refractory lining *c*.

At its lower part the said chamber is provided with a gas burner *d* supplied by pipes *e* with combustible gas under pressure and

by pipes *f*, *g*, with compressed air, the latter extending from a single pipe *h* to which is also connected a supplementary air pipe *i* opening into the chamber *a* above the burner *d*. These various pipes are provided with cocks *e¹*, *f¹*, *g¹*, *i¹*, which allow of suitably regulating the proportion of combustible gas and compressed air.

At its upper part the chamber *a* is traversed by a pipe *k* through which flows the molten material coming from a hopper *l*. The material is poured into the hopper *l* in molten condition, from any suitable crucible or furnace in which it has been melted, or is ladled from such a furnace into said hopper *l*. This pipe terminates in a nozzle *m* located in the middle of an outlet nozzle *n*, through which escape the gases produced by the combustion under pressure maintained within the chamber *a*.

Plugs *o* and *p* are provided to afford access to the chamber *a* for lighting and cleaning purposes, etc.

In the embodiment of the apparatus shown in Figs. 2, 3 and 4, the chamber *a* is divided into two compartments *a¹*, *a²* communicating with each other, one containing the furnace *d* constituting the combustion chamber proper, and the other, traversed by the feed pipe *k*, and provided with the outlet nozzle *n*, forming the chamber for heating the materials under treatment and for the discharge of the gases, so as to allow of arranging the apparatus to suit particular cases and to facilitate the erection and dismounting thereof.

The operation of the apparatus is as follows:—

The burner *d* having been lighted and the combustion properly regulated by operating the various cocks *e¹*, *f¹*, *g¹*, *i¹* the molten material is fed through the pipe *k*. During its passage through the said pipe it is heated by the flame and gases at a high temperature produced by the action of the burner. As it issues from the nozzle *m* it is atomized by the sudden expansion in the open air of the gases of combustion escaping around the said nozzle through the outlet aperture of the nozzle *n*.

The higher the pressure of the gases of combustion in the chamber *a* the finer is the state of division obtained.

The preliminary heating of the molten

materials is very important as it prevents them from solidifying, as they might toward the outlet of the nozzle *m* owing to the lowering of the temperature caused by 5 the expansion of the gases.

It is obvious that instead of a gas burner a furnace can be employed fed with a suitable solid or liquid fuel and designed to allow of maintaining combustion under pressure while adopting certain detail arrangements necessitated by the nature of the fuel 10 employed.

The hopper *l* and the feed pipe *k* are made of materials and dimensions suitable to the 15 materials to be treated.

The nozzle *m* of the feed pipe *k* may be fixed or movable, and this nozzle, as well as the outlet nozzle *n* may be of various forms.

Claims:

- 20 1. A process for the pulverization of molten materials, previously brought to the molten state, comprising producing a jet of gases produced by the combustion under pressure of a fuel and introducing the 25 molten material into said jet, said jet being concentric and parallel to the flow of said molten material into said jet, said molten

material being pulverized by the sudden expansion of said gases in the air.

2. An apparatus of the character described, comprising a conduit for melted material, and an exit nozzle for combustion gases under pressure, said nozzle surrounding the extremity of said conduit, the interior walls of said nozzle being cylindrical and concentric to the exterior surface of 35 said conduit, in such manner that the gas escapes parallelly to the flow of the fused material, whereby to entrain it at the same time that the gases produce the division and 40 pulverization of said material by their expansion into the free air.

3. An apparatus according to claim 2, further comprising a combustion chamber, and said combustion chamber having an exit 45 which forms the gas nozzle.

4. An apparatus according to claim 2, comprising a combustion chamber and a separate chamber for the combustion gases, communicating with said combustion chamber, and surrounding said melted material 50 conduit.

EUGÈNE ODAM.
